Primary Examiner—Lowell A. Larson
Attorney—Barnard, McGlynn & Reising

ABSTRACT: This invention relates to the manufacture of springs utilized in beds, seating and other furniture. In ac-

cordance with the invention separate spring sections are provided from a plurality of interconnected spring strips and each spring strip comprises an integral length of wire defining alternate right and left handed spiral coils. In each strip, a first or top end of each spiral coil is integrally connected to an adjacent spiral coil on one side thereof by a generally U-shaped section and the second or bottom end of each spiral coil is integrally connected to an adjacent spiral coil on the opposite side thereof by another generally U-shaped section. Adjacent spiral coils in each strip are hooked into mechanical interlocking engagement with one another and a plurality of helical coils interconnect adjacent strips by being disposed about legs of certain of the adjacent U-shaped sections in each strip. In accordance with the invention, the wire of each strip is severed along the base of a U-shaped section between adjacent first and second spiral coils in each strip. The spiral coils between which the wire is severed are devoid of a helical coil about the legs of the adjacent U-shaped sections at the other ends thereof so that each of the first spiral coils is in the severed section and each of the second spiral coils is in one of the strips. The strips are moved longitudinally into the severed sections and the severed sections are disposed at an inclined angle relative to the longitudinal axis of the strip to move the second spiral coils into the first spiral coils of the severed section to unhook the latter from one another so that the severed section moves free of the strips thereby providing a completely independent spring section.

SPRING MANUFACTURE

Spring assemblies to which this invention pertains are utilized in cushions, mattresses, bed springs, and other related environments. Until recently, the use of coil springs in such assemblies have been limited to individual coils connected together by independent wires, straps or the like. U.S. Pat. No. 3,188,845 discloses an apparatus for forming a single integral length of wire into a row or strip of alternately left and right handed coils which are integrally connected together, i.e., formed of a single integral piece of wire. A plurality of such rows are interconnected to provide a spring assembly. Such a spring assembly and its fabrication is described and claimed in copending application Ser. No. 636,750, filed May 8, 1967, now U.S. Pat. No. 3,476,156, in the name of John B. Simmons and assigned to the assignee of the instant invention

To manufacture a spring assembly of the type to which the instant invention pertains, a plurality of spring strips are fabricated with each spring strip comprising an integral length of wire defining alternate right and left handed spiral coils. A first or top end of each spiral coil in a strip is integrally connected to an adjacent spiral coil on one side thereof by a generally U-shaped section and the second or bottom end of each spiral coil is integrally connected to an adjacent spiral coil on the opposite side thereof by another generally U-shaped section. Adjacent spiral coils in each strip are hooked into mechanical interlocking engagement with one another by hooking convolutions thereof together, this being possible since adjacent spiral coils have opposite leads, i.e., right and left handed. A plurality of such spiral strips are disposed in side-by-side relationship and are interconnected by a plurality of helical coils disposed about legs of certain adjacent U-shaped sections in each strip and extending across the plurality of strips. Heretofore, in order to provide separate spring sections of the length desired from the interconnected strips, it has been the practice to sever the integral wire of each of the adjacent strips and thereafter utilize a tool to unhook the adjacent spiral coils which have been severed. Usually the unhooking is accomplished manually. Such a procedure is, of course, very time consuming, costly and otherwise inefficient.

Accordingly, it is an object and feature of this invention to sever the strips and dispose the severed sections relative to the spring strips so that the adjacent spiral coils, between which the wire of each strip has been severed, will automatically unhook from one another to provide a completely independent section or spring assembly.

Another object and feature of this invention is to provide a separate spring section or assembly by severing adjacent spiral coils in the respective spring strips and thereafter disposing the severed section at an inclined angle relative to the longitudinal axes of the plurality of strips while moving the plurality of strips into the severed section so that the spiral coils of the severed section automatically unhook from the spiral coils of the plurality of strips.

Other objects, features and attendant advantages of the present invention will be readily appreciated as the same becomes better understood by reference to the following detailed description when considered in connection with the accompanying drawings wherein:

FIG. 1 is a fragmentary elevational view of a spring strip comprising an integral length of wire defining alternate right and left-handed spiral coils;

FIG. 2 is a view similar to FIG. 1 showing the spring strip after having been severed with the severed section disposed at an inclined angle relative to the longitudinal axis of the strip;

FIG. 3 is a view similar to FIGS. 1 and 2 but showing the severed section completely detached from the main portion of the spring strip;

FIG. 4 is a perspective view looking downwardly at an angle of approximately 45° to the spring strip immediately after having been severed;

FIG. 5 is also a perspective view looking downward at approximately 45° and showing the severed section disposed at an inclined angle relative to the main portion of the spring strip as is shown in elevation in FIG. 2; and

FIG. 6 is a perspective view looking downward at approximately 45° and showing the severed section being completely detached from the main spring strip and, in addition, shows adjacent spring strips interconnected by a helical coil.

Referring now to the drawings wherein like numerals indicate like or corresponding parts throughout the several views, there is shown generally at 10 a spring strip of the type to which the instant invention pertains.

A plurality of spring strips 10 are shown disposed in side-by-side and interconnected relationship in FIG. 6. Each spring strip 10 comprises an integral length of wire defining alternate right and left-handed spiral coils 12 and 13. A first or top end of each spiral coil is integrally connected to an adjacent spiral coil on one side thereof by a generally U-shaped section 14. Each spiral coil, at the second or bottom end, is also integrally connected to the adjacent spiral coil on the opposite side thereof by another generally U-shape section 16. Each U-shaped section, as illustrated in the preferred embodiment, includes a pair of spaced parallel legs with an interconnecting base portion, the legs being integrally connected to the spiral coils at one end and the base portion at the other end.

Adjacent spiral coils in each strip are hooked into mechanical interlocking engagement with one another. More specifically and as best illustrated in FIGS. 1 and 4, the adjacent spiral coils 12' and 13' are hooked into mechanical interlocking engagement as indicated at 20 and 22. The bottom convolution of the spiral coil 12' is mechanically hooked into engagement with the bottom convolution of the spiral coil 13' whereas the upper convolution of the spiral coil 12' is hooked into mechanical interlocking engagement with the next adjacent spiral coil 13 at the top thereof. It will be noted that the hooking engagement at 22 is the result of the leg portions of adjacent U-shaped sections 16 crossing one another while the hooking engagement at 20 is the crossing of a convolution of each of the adjacent spring strips. As alluded to previously, the adjacent spiral coils are hooked into mechanical interlocking engagement with one another after the respective spiral coils have been made, one method of hooking the adjacent spiral coils together being illustrated in the aforementioned U.S. Pat. No. 3,188,845.

As illustrated in FIG. 6, a plurality of strips 10 are disposed in side-by-side relationship and are interconnected by a plurality of helical coils 24. Each helical coil 24 is disposed about legs of certain adjacent U-shaped sections 14 and 16 in each strip. However, the mechanical hooked engagement at 22 of legs of adjacent U-shaped sections 16 is devoid of a helical coil 24. The helical coils 24 are disposed in position after the adjacent coils in each spring strip are hooked into mechanical interlocking engagement. During this process a helical coil 24 is not provided at certain distances along the plurality of strips. The helical coils 24 are not provided at certain positions along the respective strips and these positions depend upon the length of the sections desired to be severed. In other words, if it is desired to make box springs which are 6 feet in length, the strips will be severed at 6 feet intervals and therefore the strips will be devoid of a helical coil at 6 foot intervals.

As has been thus far described, therefore, a plurality of spring strips each comprising identical lengths of wire defining alternate and right-handed spiral coils are disposed in side-by-side relationship and interconnected by a plurality of helical coils 24 to provide the assembly as illustrated in FIG. 1. When the plurality of spring strips are thus interconnected as illustrated in FIG. 1, the plurality of strips are severed to provide separate sections in accordance with the instant invention.

In accordance with the instant invention, the wire defining each spring strip is severed by an appropriate severing means or cutting instrument such as that illustrated at 26. The wire of each spring strip may be severed in accordance with the invention set forth in the aforementioned patent application Ser. No. 636,750. As illustrated, each spring strip is severed along the base portion of a U-shaped section 14. The wire is severed between adjacent first and second spiral coils 12' and 13' and these spiral coils are devoid of a helical coil 24 about the legs

of the adjacent U-shaped section 16 at the other ends thereof as illustrated at 22. Thus, each of the first spiral coils 13' is in the severed section and each of the second spiral coils 12' is in the unsevered or main strip portion.

After the strips have been severed as shown in FIG. 1, the unsevered portion or strip portion containing the spiral coils 12' is moved longitudinally into and toward the severed section containing the spiral coils 13'. The plurality of strips containing the spiral coils 12' are moved along a support means comprising a horizontal surface 28 and there is included means comprising a second surface 30 for disposing the severed section containing the spiral coils 13' at an inclined angle relative to the longitudinal axis of the strips, as illustrated in FIGS. 2, 4 and 5. The surface 30 is in a different plane than the plane of the horizontal surface 28 and the surface 30 is parallel to and below the horizontal surface 28.

The severed section containing the spiral coils 13' is therefore disposed at an inclined angle relative to the longitudinal axis of the strip containing the spiral coils 12' so that as the strips containing the spiral coils 12' are moved longitudinally they move into the spiral coils 13' as best illustrated in FIGS. 2 and 5. As the spiral coils 12' move into the spiral coils 13', the spiral coils 13' become unhooked from the spiral coils 12' so that the severed section moves in a direction which is transverse to the longitudinal axis of the strip containing the spiral coils 12' or drops downward under the force of gravity to the completely disconnected position illustrated in FIGS. 3 and 6. To recapitulate, each spring strip is severed at position opposite a pair of adjacent U-shaped portions 16 which are not interconnected with adjacent spring strips by a helical coil 24 and the severed section is disposed at an inclined angle relative to the longitudinal axis of the spring strip. The spring strips, and thus the spiral coils 12', are moved into the spiral coils 13' to the position illustrated in FIG. 5 where the severed sections including the spiral coils 13' fall due to gravity free from the spring strips containing the spiral coils 12', thereby providing a completely independent section. Each independent section is thereafter formed into a spring assembly such as a bed spring.

Although the invention has been illustrated in a manner wherein the severed section is inclined at a downward angle relative to the spring strip containing the spiral coil 12' it will be understood that the strips may be severed along the base portion of a U-shaped section 16 with the severed section disposed at an inclined angle upward from the spring strip so that as the spring strips move into the severed sections the severed sections may be moved upward to provide a completely independent section.

I claim:

1. A method of providing separate sections from a continuous spring strip of an integral length of wire defining alternate right and left-handed spiral coils with coils of adjacent spirals hooked into mechanical interlocking engagement with one another, said method comprising; severing the wire between adjacent first and second spiral coils to provide an independent section with the first spiral coil in said strip and the second spiral coil in said section, moving said strip longitudinally of itself so as to also move said section, and disposing said section at an inclined angle relative to the movement of said strip so that said first spiral coil moves into said second

spiral coil to unhook the coils thereof from one another.

2. A method as set forth in claim 1 including moving said strip along a substantially horizontal surface.

3. A method as set forth in claim 2 including disposing said section at an inclined angle downward relative to the direction of movement of said strip.

4. A method as set forth in claim 3 including allowing said section to unhook from said strip by gravity.

5. A method as set forth in claim 2 including a plurality of said strips disposed in side-by-side relationship and interconnected by a plurality of helical coils and wherein said method includes severing the plurality of strips, moving the plurality of strips, and inclining the interconnected sections to unhook the latter from the plurality of strips.

6. A method of providing separate sections from a plurality of spring strips each of which comprises an integral length of wire defining alternate right and left-handed spiral coils with a first end of each spiral coil integrally connected to an adjacent spiral coil on one side thereof by a generally U-shaped section and the second end of each spiral coil integrally connected to an adjacent spiral coil on the opposite side thereof by another generally U-shaped section and with adjacent spiral coils of each strip hooked into mechanical interlocking engagement with one another and a plurality of helical coils interconnecting adjacent strips by being disposed about legs of certain adjacent U-shaped sections in each strip, said method comprising severing the wire of each strip along the base of a U-shaped section between adjacent first and second spiral coils which are devoid of a helical coil about the legs of the adjacent U-shaped sections at the other ends thereof so that each of said first spiral coils is in said severed section and each of said second spiral coils is in said strip, moving the plurality of strips longitudinally and into said severed section, disposing said severed section at an inclined angle relative to the longitudinal axis of said strips to move each of said second spiral coils into said first spiral coils to unhook the latter from the second spiral coils thereby providing a completely independent section.

7. An apparatus for providing separate sections from a continuous spring strip of an integral length of wire defining alternate right and left-handed spiral coils with coils of adjacent spirals hooked into mechanical interlocking engagement with one another, said apparatus comprising, support means for supporting said strip for movement longitudinally of itself, severing means for severing the wire between adjacent coils to provide an independent section, and means for disposing said section at an angle inclined to the longitudinal axis of said strip and allowing said section to move in a direction transverse to the longitudinal axis of said strip so that said section unhooks from said strip as said strip is moved into the inclined section.

8. An apparatus as set forth in claim 7 wherein said support means comprises a horizontal surface.

9. An apparatus as set forth in claim 8 wherein said means for disposing said section at an angle and for allowing transverse movement of said section includes a second surface in a different plane than the plane of said horizontal surface.

10. An apparatus as set forth in claim 9 wherein said second surface is parallel to and below said horizontal surface.
